ATTORNEY

UNITED STATES PATENT OFFICE.

DONALD STEWART, OF WATERLOO, IOWA.

CABINET.

1,295,232.

Specification of Letters Patent. Patented Feb. 25, 1919.

Application filed June 13, 1917. Serial No. 174,547.

To all whom it may concern:

Be it known that I, DONALD STEWART, a citizen of the United States, residing at Waterloo, in the county of Blackhawk and State of Iowa, have invented certain new and useful Improvements in Cabinets, of which the following is a specification.

The present invention relates to cabinets and is particularly concerned with that type 10 of cabinet designed for containing salt, pepper, spices, tea, coffee and the like.

It is the object of this invention to provide a cabinet which will retain such articles as above mentioned in an orderly manner and which is so constructed as to present the desirous condiments or article to the user upon proper manipulation of certain actuating means, the other articles contained in the cabinet being concealed and inaccessible during the presentation of the desired article.

The invention resides in the provision of a housing having a door or window therein and a rotatable holder comprising a plurality of compartments each of which is presented in succession before the said door or window, each compartment being adapted to have an article or a particular condiment placed therein.

Other features of the invention will be apparent from the following description, which clearly sets forth the construction, combination and arrangement of parts, and from the appended claim.

In the drawings,

Figure 1 is a side elevation of a cabinet constructed in accordance with the invention,

Fig. 2 is a vertical sectional view taken 40 through the cabinet, and

Fig. 3 is a horizontal sectional view taken substantially on line 3-3 of Fig. 2.

Like characters denote similar and like parts throughout the specification and drawings.

The cabinet according to the invention may be of any desired size and may be incorporated in the combination kitchen cabinets now extensively used. The invention consists, more in detail, of a housing, of any particular shape, having in one of its walls an opening 2 closed by a door 3 hinged to a housing as indicated at 4. The door 3 is constructed with a glass window 5 or other sight opening 5 and may be held in its closed position by a latch means 6. The

housing 1 may be of such size as to contain several revolving holders 7 (Figs. 2 and 3) and, in such instances, the housing 1 is provided with a corresponding number of openings 2, as shown in Fig. 1, for a purpose which will be readily apparent from a better understanding of the invention.

Each holder 7 comprises a horizontal platform *a* supported by the vertical shaft 8 extending through the center thereof and journaled at its ends in the bearings 9 secured to the upper and lower walls of the housing 1. A plurality of vertical partitions *b* are radially disposed on the upper surface of the platform to provide a plurality of compartments or stalls *c* covered by a top board *d*. Each revolving holder 7 can be positioned in the housing adjacent an opening 2 so that the articles therein may be reached. A bevelled gear 10 is carried on the shaft 8 below the holder and meshes with another gear 11 on the horizontal shaft 12. This shaft 12 has its inner end journaled in the bearing 13 projecting from the lower bearing 9, above referred to, and has its outer end journaled in and extended through the side wall of the housing, just below the opening 2, the outer extremity of the shaft carrying a pointer 14. A dial 15 is arranged about the outer end of the shaft 12 with which the pointer 14 co-operates.

It is contemplated by my invention to have the names of the various ingredients or articles marked on the dial at uniformly spaced intervals and each rotation of the holder 7 about its axis will cause one complete rotation of the pointer 14, which is so positioned that, when one of the compartments *c* is before the door-opening 2, the pointer will indicate upon the dial the particular article or condiment which is presented. It being understood, of course, that the door-opening 2 is only of sufficient size as would permit an unobstructed access to the compartment which is before the opening.

It will, therefore, be obvious that should it be desired to obtain a particular condiment or article in the cabinet it would only be necessary to move the pointer 14 to the point on the dial naming that condiment and the rotation of the pointer will cause the holder 7 to rotate sufficiently to present the compartment thereof containing the desired condiment before the door-opening 2. Manifestly, the present invention provides a means for containing the various articles or

ingredients in an orderly manner and will present them for use systematically and without mistake, because the pointer will always indicate that particular condiment before the opening of the cabinet. The compartments of the holders 7 are designed to retain bottles, jars or other containers 16, indicated in dotted lines, and which initially contain the condiments however, the compartments themselves may be constructed to initially contain the condiments. In the present construction, when it is desired to replace the containers 16 in the cabinet, the user will see that the pointer 14 indicates on the dial that the proper compartment for receiving the particular condiment or article is in position before the door-opening 2, and in this manner an orderly and systematic operation of the cabinet is obtained.

The above clearly describes my invention, however, it is to be understood that in the construction, combination and arrangement of parts changes may be resorted to that fall within the legitimate scope of the appended claim.

What is claimed is:
A cabinet comprising a housing having

an opening in one wall intermediate the top and bottom, a closure for the opening, a bearing plate secured to the inner side of the bottom of the housing, a bearing plate secured to the inner side of the top of the housing, a vertical shaft rotatably mounted in the plates, a platform carried by the shaft, said platform being positioned adjacent the bottom edge of the opening in the wall, a gear connected to the vertical shaft, a bearing arm connected to the bottom bearing plate adjacent the vertical shaft, a horizontal shaft having one end received in the bearing arm and the opposite end passing through the wall of the housing, a gear secured to the horizontal shaft and meshing with the gear on the vertical shaft, a dial plate secured to the outer face of the wall containing the opening, and a pointer secured to the outer end of the horizontal shaft and operating around the dial.

In testimony whereof I affix my signature in presence of two witnesses.

DONALD STEWART.
